SKIP-STOP CONTROL MECHANISM

Filed Aug. 9, 1934

UNITED STATES PATENT OFFICE

2,044,076

SKIP-STOP CONTROL MECHANISM

Albert M. Johnson, Rockford, Ill., assignor to
 Barnes Drill Company, Rockford, Ill., a corporation of Illinois.

Application August 9, 1934, Serial No. 739,124

17 Claims. (Cl. 74—27)

The present invention relates to improvements in control means adapted for defining the limits of the reciprocatory movements of an operating device, wherein it is desirable that the control be adjustable with ease and precision, and has particular reference to an adjustable control device including a stop bar having adjustable stop members thereon for defining the limits of movement of an operating member longitudinally of the bar.

A common form of control mechanism found desirable for this purpose includes the combination of principal stops and skip-stop means which will determine not only the utmost limits of reciprocation of the operating member but will also, where desired, confine the reciprocations thereof within more restricted limits. The various stops of the control must be accurately positioned to secure best results. Moreover, it is often desirable to make slight or radical adjustments before or after the machine is in operation so as to vary the stroke of the reciprocating parts, to the accomplishment of which it has heretofore been necessary to halt the machine and adjust the stops by means of set screws or similar relatively cumbersome expedients.

The primary object of the present invention, therefore, resides in the provision of novel adjustment means for controls which embody a bar carrying stops for limiting the reciprocatory movement of an operating member, and in which the relative position of the stops may be easily and accurately adjusted without interfering with the normal operation of the associated machine.

Another object is to provide an improved skip-stop control device of the foregoing character which can be adjusted by a screw action to regulate with precision the length of the reciprocations of the operating member and which will remain in proper adjustment in spite of repeated concussions incident to contact of the operating member with the stops.

Another object resides in the provision of an improved control mechanism of the foregoing character including an adjustable stop having a screw threaded part cooperative with complementary means on the stop bar whereby adjustment of the stop on the bar may be effected by simple manipulation without the use of tools.

Another object of the invention is to provide improved control means of the foregoing character in which the stop members are freely adjustable on the stop bar, and in which means are provided for substantially locking the stop members against disturbance of the precise relative

adjustment thereof due to concussion incidental to operation of the machine.

Another object is to provide a control device including a bar and a member longitudinally adjustable thereon, in which the member comprises a part slidable on the bar and a part provided with screw threads adapted to mesh with complementary means on the rod whereby rotation of the threaded part will determine a substantially micrometer adjustment of the member.

Other objects and advantages will become apparent in the following description and from the accompanying drawing, in which:

Figure 1 is a fragmentary elevational view partly in section of one form of the invention.

Fig. 2 is a sectional plan view taken on line 2—2 of Fig. 1.

Fig. 3 is a fragmentary elevational view partly in section of a different form of the invention.

Fig. 4 is a sectional plan view taken on lines 4—4 of Fig. 3.

Fig. 5 is a fragmentary sectional elevation showing one of the stops of the form of the invention shown in Fig. 3 in unlocked position to permit substantial vertical movement of the stop member.

While the invention is susceptible of various modifications and alternative constructions, I have shown in the drawing and will herein describe in detail the preferred embodiments, but it is to be understood that I do not hereby intend to limit the invention to the specific forms disclosed, but intend to cover all modifications and alternative constructions falling within the spirit and scope of the invention as expressed in the appended claims.

The improved adjustable control means of the present invention may be used in various machines, but it has been found of particular merit for use in connection with honing machines such, for example, as described in Patent No. 1,783,019, issued to me on November 24, 1930, wherein a reciprocating head supports spindles carrying hones for operating upon internal cylindrical bearing surfaces. In such a machine the reciprocatory movements of the head must be accurately controlled so that the length of stroke of the hone will be within proper limits for the surface being honed.

The means for controlling reciprocation may comprise a stop bar mounted with its axis parallel to the reciprocatory movements of the moving machine part and having spaced stops adapted to be engaged by a stroke arm such as a lug or other projecting element associated with the said recip-

reciprocating part of the machine. The stops are preferably adjustable to vary the amplitude of reciprocation of the said stroke arm as desired, and a salient feature of the present invention resides in the provision of manually operated screw threaded adjusting means for accomplishing this result.

Referring more specifically to the drawing, a stop bar 10 of substantial length is suitably supported by means, not shown, adjacent a reciprocable part of a machine and may be of hexagonal or any other similar geometric cross section to provide a plurality of relatively flat faces 12 about its periphery (Figs. 1 and 2). Principal stop members 14 and 15, which may be in the form of disks of substantial diameter and which are provided with internal screw threads 16, fit about the bar 10 and engage complementary means thereon which may take the form of threaded sections 17 tapped in the areas of predominating radius on the periphery of the bar. A stroke arm 18 associated with the reciprocable part of the machine is positioned for longitudinal movement between the stops 14 and 15 and is adapted to engage with a face 19 on each stop. The arm 18 will strike the stops with some force and each of the stops 14 and 15 is therefore provided with an integral collar section 20 which is also internally screw threaded and engages with the threads 17 on the bar. This increases the area of engagement between the bar and the stop members whereby the stability and rigidity of the stops is assured even under the repeated concussions of the arm 18 therewith.

35 The force of the concussions incident to operation of member 18 may tend gradually to force the stops out of adjusted position and to prevent this accidental movement of the stops, resilient locking means is associated therewith. A simple 40 form of locking means is shown by way of example, and consists of a radial aperture 22 formed in each stop and adapted to receive a ball 23. A spring 24 engages the ball to urge the same into contact with one of the engagement faces 45 12 of the bar 10, and a screw plug 25 is received in an outer threaded portion 26 of the aperture 22 to bear against the outer end of the spring and place the same under tension. When the disks 14 or 15 are rotated, the ball 23 will be successively and resiliently wedged against each face 12 of the bar 10 and will tend to maintain the stop against accidental movement until the same is positively manually urged into another position. The minuteness of adjustment possible with this form of control device, therefore, is proportionate to the pitch of the threads 16 and 17 and the number of engagement faces 12 with which the locking ball 22 may successively engage.

60 Where the movements of the reciprocatory member of the machine in conjunction with which the control means is used must be varied for different periods of operation, it is desirable to provide skip-stop means intermediate the principal stops whereby periodically to confine reciprocations of the stroke arm to a stroke of defined amplitude less than the full stroke between said principal stops. As an example of an expedient for accomplishing this result with the control means of the present invention, there is shown as mounted on the bar 10 intermediate the principal stops 14 and 15, a skip-stop member 28 which is adapted to confine the reciprocatory strokes of arm 18, and thereby of the reciprocating machinery associated therewith, to an am-

plitude defined by the space between the skip-stop and one of the principal stops.

The skip-stop 28 comprises as one element an adjustment member which may be in the form of a disk 30 encircling bar 10 and of a diameter substantially less than that of the stops 14 and 15 so that lug 18 may pass freely thereby. The disk 30 is internally screw threaded to engage with threads 17 on the bar and has a compression lock comprising a radial aperture 31 within which is received a ball 32 resiliently urged into engagement with one of the faces 12 of the bar 10 by means of spring 33 which is held in place by a screw plug 34. Adjustment of the member 30 on the bar 10 is effected by screwing the same one way or the other on the bar.

The principal portion of the skip-stop may comprise a block 35 non-rotatably mounted on the bar 10 but freely slidably longitudinally thereof. The block 35 is connected with the disk 30 in a manner to permit free rotation of the disk to effect adjustment of the skip-stop on the bar 10. Thus, a collar 36 is formed on disk 30 and has an annular recess 37 in which a segmental rim 38 formed on an upward extension 39 on one face 25 of the block 35 is slidably received.

The contact face of the skip-stop for engagement with the lug 18 may be formed as an integral part of block 35, but a desirable arrangement is secured through the provision of a lever 42 comprising a bifurcated body embracing the block 35 and pivotally mounted thereon. The free ends of the bifurcated arms of the lever 42 are secured on a pivot pin 43 extending through the block, and the crotch of the lever extends 35 under the lower end of the block for pivotal movement into and out of engagement therewith. A lateral lug 45 is formed on one or both of the arms of lever 42 and has a recess 46 in one face. A coil compression spring 47 seated at one end 40 in the recess 46 and abutting at its other end against a fixed lug 49 on the block 35, tends to hold the crotch of the lever against the lower end of the block. Suitably secured in the crotch of the lever 42 or formed as a part thereof, and 45 extending outwardly therefrom is a pawl 50 having a horizontal contact surface 51 and an inclined end contact surface 52.

The members 14 and 15 are adapted to define the uppermost and lowermost limits of movement 50 of the stroke arm 18, and the skip-stop 28 provides a control for the uppermost limit of movement of the stroke arm during certain periods in the operations of the associated machine. Thus, when the arm 18 is carried downwardly it 55 will engage against the inclined face 52 on the pawl 50, which will cause the spring means 47 to compress and allow the lever arms 42 to move in clockwise direction as viewed in Fig. 1 to permit the arm to pass beyond the pawl. Thereupon, the 60 spring means 47 will urge the crotch of the lever 42 back into engagement with the block 35 and face 51 of the pawl will be interposed in the path of the arm 18 so that further upward movement thereof will be limited. Means, not shown, may 65 be provided for turning the bar 10 about its axis when it is desired to move the pawl 50 out of the path of arm 18 to allow the latter to travel to the utmost limit defined by face 19 of stop 14.

The above described control means is advantageous where accurate adjustment of the respective stops is desired for operation upon work of standard character and where once an adjusted relationship has been secured no radical changes will ordinarily be necessary for a sub- 75

stantial time. However, in some machines it may become desirable not only to effect a micrometer adjustment of the stops but also to provide for quickly and substantially varying the relative positions of the stops in order to accommodate varying operative requirements. As an example, reference may be had to cylinder honing machines in which it is necessary to adjust the control to vary the stroke of the hones to operate upon cylinders of different lengths.

The form of the invention exemplified in Fig. 3 has been found desirable in meeting the last mentioned requirements, and provides a control embodying yieldable means serving to prevent accidental movement of the stops after the desired micrometer adjustment has been effected, but permits quick shifting of the stops longitudinally of the bar when a revised relationship of the stops is necessary.

As an essential part of the modified control there is provided a stop bar 55 which may be round or of any other desired geometric cross section and is adapted to be suitably supported on a machine to be controlled. Upon the bar are slidably mounted principal stops 56 and 57 of preferably similar construction and having associated rotatably mounted worm wheel adjusting members 58, preferably disposed with their axes parallel to bar 55. The threads of worms 58 are adapted to engage with complementary means on the bar 55, such as a rack 60 milled longitudinally thereof.

In the following description the construction of the lower stop 57 will be particularly referred to but due to the similarity of detail of the upper stop 56, the description is equally applicable thereto. The worm 58 is rotatable on a pintle 62 secured to or forming a part of a lever 63 which is pivotally mounted in a radial slot 64 formed in the stop member. A pin 65 extends through a collar 66 on the stop and through lever 63 and serves as the pivot therefor. A collar 67 is suitably secured to the outer end of pintle 62 for retaining the worm 58. The opposite end of the lever 63 has an outwardly extending flange 68 provided with a suitable aperture to slidably receive a pin 69. A plate 70 is secured to one end of pin 69 in any suitable manner such as by means of a screw or a rivet head formed on a reduced portion 71 of the pin 69. A plate 73 is similarly secured to the other end of pin 69 which is similarly formed with a reduced end 74. The pin 69 is surrounded by a compression spring 75 which resiliently engages the opposed faces of the flange 68 and the plate 70 to normally force the same apart and to pull the plate 73 into abutment with the flange 68. A wedge-like finger or detent 77 is formed on the inner edge of the plate 73 and fits between the inner edge of the flange 68 and an abutment 79 formed as a part of the stop and extending across the inner end of the recess 64. The detent 77 serves to lock the lever 63 against movement and thereby prevents displacement of the worm 58 from the rack 60.

The outer edge of the threads of the worms 58 are preferably knurled to facilitate manipulation, and a micrometer adjustment of the stops 56 and 57 longitudinally of the shaft is effected by rotation of the worms in mesh with the rack 60. However, when it is desired to more radically adjust the position of the stops on the bar 55, pressure upon the plate 70 will compress the spring 75 and force the pin 69 through the flange 68 to carry the plate 73 away from the flange and thus

remove the detent 77 out of the recess 64. This will permit the lever 63 to pivot on the pin 65 to carry the worm 58 out of engagement with the rack 60 (see Fig. 5), whereupon the stop may be slidably adjusted to any desired position on the bar 55. Upon releasing pressure on the plate 70, the spring 75 will force the associated parts back to normal position and cause the detent 77 again to enter into the recess 64, whereby the worm 58 will again be carried into engagement with the rack 60. The stop may then be adjusted with micrometer exactness to the precise position desired.

An intermediate skip-stop 81, having similar functions as the skip-stop 28 hereinbefore described, is preferably formed as a block 82 slideable longitudinally of the bar 55. The block 82 may be of rectangular shape and of transverse dimensions less than that of the stops 56 and 57. A worm 83 is provided for engagement with the rack 60 to effect micrometer adjustment and is operatively associated with yieldable means of a similar character to that described in connection with the stop 57 for locking the skip-stop against accidental displacement. Thus, stop 81 may be moved to any desired position intermediate stops 56 and 57 and adjusted with micrometer precision.

A suitable skip lever 84 embraces the block 82 and is pivotally mounted thereon by means of a pin 85. The lever 84 is similar in construction and function to the lever 42 hereinbefore described and has a pawl 87 which serves to limit upward movement of a stroke arm 88 after the latter has been carried past the skip-stop 81. The bar 55 may be provided with means, similarly as the bar 10, for imparting relative movement about its axis to remove the pawl 87 from the path of the arm 88 so that the arm may complete a full stroke between the principal stops. The resilient locking means hereinbefore described, will prevent disengagement of the worms 58 and 82, and the stops will thus be maintained against accidental movement due to concussion incident to contact with the arm 88.

From the foregoing it will appear that the invention provides adjustable control means of an improved character for machines having reciprocable parts, and adjustment of the control may be effected with ease and precision even while the machine is in operation. The control is provided with stops which are mounted to effect micrometer adjustment, and which embody yieldable locking means serving to prevent accidental movement of the stops. In addition, by somewhat modifying the construction, the stops are adapted for substantial slidable relative adjustment as well as micrometer screw adjustment.

I claim as my invention:

1. In a control device for machine tools, in combination, a bar, a member encircling said bar and movable longitudinally thereof, means for adjusting the position of said member on said bar and including a threaded part on said member cooperative with complementary means on said bar to receive the threads of said part whereby movement of said member on the bar is effected by simple manipulation to adjust said threaded part relative to said complementary means, and locking means carried by said member for retaining said member in adjusted position on said bar and for preventing accidental movement of the member relative to the bar.
2. In a control device for a machine having a

- reciprocating moving part, in combination, a bar, a member mounted on said bar and adjustable longitudinally thereof, said member being positioned adjacent a reciprocable operating element 5 of the machine movable adjacent said bar and intermittently contacting said member with relative force, means for accurately adjusting the position of said member on said bar and including a threaded part on said member in engagement with complementary means on said bar co-acting with the threads thereof, and locking means embodying a movable locking element and yieldable compression means carried by said member for retaining the same in adjusted position 10 on said bar in spite of concussion incident to forceful contact between said member and said element.

3. A skip-stop control device comprising in combination, a stop bar, a pair of principal stops 20 in substantially spaced relationship on said bar, a skip-stop on said bar intermediate said principal stops, means for precision adjustment of said skip-stop relative to said principal stops and including a rotatable screw threaded member, 25 complementary means on said bar engageable by the threads of said member, and means embodying a locking wedge carried by said skip-stop for holding said member in a given relation with respect to said bar and thereby retaining the same 30 in adjusted position against accidental movement.

4. In a skip-stop control device for machine tools, a bar, a stop slideable on said bar including a movable element and a part encircling said bar 35 and relatively movable between the ends of the bar, screw threaded means carried by said element, means on said bar and extending throughout a substantial portion of the length of the bar and engageable by said screw threaded 40 means whereby adjustment of said stop on said bar is effected by relative screw action between said means, and yieldable locking means including a part normally disposed to prevent movement of said movable element.

45 5. A control stop mechanism for machine tools comprising a bar, an internally threaded manually adjustable stop member on said bar, complementary means in the form of screw threads on said bar and adapted to be engaged by the threads of said stop, an engaging face on said bar, and yieldable means associated with said stop and engaging with said face to prevent accidental movement of the stop relative to the bar.

55 6. A control stop mechanism for machine tools comprising a bar, an internally threaded manually adjustable stop in engagement with said bar, complementary means in the form of threaded sections tapped in the periphery of said bar and 60 in engagement with the threads of said stop, a longitudinal engaging face on said bar, a radial recess in said stop, and yieldable means in said recess and in engagement with said face to prevent accidental movement of said stop relative to the bar.

65 7. In a control stop device of the character described, in combination, a bar, a stop member embracing said bar and adapted for longitudinal movement thereon, said member including a block having an integral extension on one face provided with a segmental rim, an annular internally threaded member having an integral collar provided with an annular recess for slidably receiving said segmental rim, and complementary screw threads on said bar engaged by said an-

nular member whereby rotation of said annular member will move said stop member.

8. In a control stop device for machine tools, a bar, a stop slideable on said bar, a lever member pivotally associated with said stop, a worm carried by said lever member, means on said bar engageable with said worm whereby rotation of said worm effects relative longitudinal movement of the stop relative to the bar, and a manually operable yieldable lock movable into and out of engagement with said lever for positively retaining said worm in engagement with said bar.

9. In a control device for machine tools, a bar, a stop slideable on said bar, a lever pivotally associated with said stop, a worm carried by said lever, means on said bar engageable with said worm whereby rotation of said worm effects relative longitudinal movement of the stop on the bar, and a lock movable into and out of engagement with said lever including a compression spring for holding the lock in locking condition to normally maintain said worm in engagement with said bar.

10. In a device of the character described, a bar, a stop on said bar including a member movable into and out of engagement with said bar, means on said bar engageable by said member, means for moving said member, and locking means for maintaining said member in engagement with said bar including a detent and a compression spring for resiliently forcing said detent into position, said detent being releasable incident to movement of said member out of engagement with said bar.

11. In a control device, a bar, a stop member 35 slideable longitudinally of said bar, a lever pivotally mounted on said stop and having an end spaced from said bar, a rotatable externally threaded element carried by said lever and movable toward and away from said bar, complementary means in the form of a rack on said bar and engageable by said element to provide for screw adjustment of the stop on said bar, and a part adapted to be normally wedged between the spaced end of said lever and said bar to prevent 40 movement of the lever relative to the bar.

12. In a control device of the character described, a bar, a stop slideable longitudinally of said bar, a member pivotally connected with said stop, a worm rotatably carried by said member, complementary means in the form of a rack on said bar and adapted to be engaged by said worm whereby rotation of said worm will effect minute adjustment of the position of said stop on said bar, and means carried by said member 45 for locking the same against pivotal movement and including a lock part movable into and out of engagement therewith and a spring normally urging said part into locking relationship with said member, said spring being yieldable under 50 manual force to remove said part from locking relationship, whereby said worm may be removed from engagement with said rack and the stop slidably moved relative to said bar.

13. In a control device, a bar, a stop member 55 slideable longitudinally of said bar, said member having a slot formed therein, a lever pivotal in said slot, a worm rotatably attached to one end of said lever, complementary means in the nature of a rack formed on said bar and engageable by said worm to provide for micrometer adjustment of said stop on said bar, a flange on the opposite end of said lever, a pin slidable in an aperture formed in said flange, a pair of 60

plates attached to opposite ends of said pin, a compression spring between one of said plates and said flange, the flange end of said lever being spaced from the body of said stop, and a detent formed on one of said plates and engageable in the space between said end and body to lock said lever and prevent disengagement of said lever except when said detent is removed from locking position by compressing said spring to move said pin and attached plates out of locking position.

14. In a skip-stop control device for machine tools, a bar having a longitudinal engagement portion in its periphery, a stop encircling said bar and adapted for longitudinal movement thereon, screw-threaded means on said stop, means on said bar adapted for cooperative engagement with said screw-threaded means whereby to effect micrometer adjustment of said stop on said bar, and yieldable retaining means carried by said stop cooperative with said engagement portion to prevent unintentional movement of said stop relative to said bar.

15. In a skip-stop control device for machine tools, a bar having a plurality of longitudinal engagement portions and alternate laterally projecting portions in circumferentially spaced relation about its periphery, screw threads formed in said projecting portions, a rotary and longitudinally movable stop member encircling said bar and internally threaded to coat with the screw threads on said bar, and yieldable means carried by said stop member cooperative with said engagement portions for retaining said stop member against unintentional movement relative to said bar, the number and spacing of said engagement faces and the pitch of said screw threads being determinative of the degree of longitudinal movement possible upon rotation of said stop to carry said yieldable means from one

engagement face to an immediately adjoining face.

16. In a skip-stop control mechanism for machine tools, in combination, a cylindrical bar having a rack formed longitudinally thereof, a member encircling said bar and longitudinally and rotatably slidable thereon, movable means carried by said bar and including a threaded element engageable with said rack, said threaded element being rotatable to adjust the member by slight degrees longitudinally of the bar, and means for locking said movable means to prevent displacement of said threaded element from said rack, whereby said member will be retained against unintentional rotary and longitudinal movement relative to said bar.

17. In a control device for a machine tool having a reciprocating moving part, in combination, a stop bar, a pair of principal stop members mounted in spaced relation on said bar, said stop members being disposed on opposite sides of an operating element carried by the reciprocable part of the machine and alternately engageable thereby to define the utmost limits of reciprocation of said part, one of said stop members having a threaded connection with the bar whereby precision adjustment of the relative spacing of the members may be effected, a skip-stop member mounted on said bar intermediate said principal stop members and engageable by said operating element to confine the reciprocation of said part of the machine within more restricted limits, said skip-stop member having a threaded connection with the bar whereby precision adjustment of the member relative to the principal stop members may be effected, and means for retaining said one principal stop member and said skip-stop member in adjusted position on said bar against accidental movement relative to the bar.

ALBERT M. JOHNSON.
